FRONT FENDER FLASHING TURN SIGNAL

Robert D. Kahn, Rockville Centre, N.Y., assignor to
Fedtro, Inc., Rockville Centre, N.Y., a corporation

Filed Apr. 4, 1966, Ser. No. 1,763

Term of patent 14 years

(Cl. D48—32)

FIG. 1

FIG. 2

FIG. 3

FIG. 4

FIG. 5

FIG. 6

FIG. 1 is a front elevational view of a front fender flashing turn signal showing my new design;

FIG. 2 is a rear elevational view thereof;

FIG. 3 is a right side view thereof;

FIG. 4 is a left side view thereof;

FIG. 5 is a top plan view thereof; and

FIG. 6 is a bottom plan view thereof.

The characteristic features of my design reside in the reflective pattern on the lens, as shown.

I claim:

The ornamental design for a front fender flashing turn signal, substantially as shown and described.
